UNITED STATES PATENT OFFICE.

HUBERT NOTEBOOM, OF PHILADELPHIA, PENNSYLVANIA.

VENDING MACHINE.

Application filed April 23, 1924. Serial No. 708,497.

This invention relates to vending machines, and an object of the invention is to provide a coin operated vending machine particularly designed for vending flat, preferably elongated articles, such as combs.

Another object of this invention is to provide a vending machine as specified which will vend combs or similar articles in an economical, expeditious manner, and which is properly designed for use in railway stations, hotels, or analogous places frequented by the public, whereby they can obtain an efficient comb at a minimum expense, and also to provide a vending machine which is easy to operate and is designed to reduce to a minimum, liability of clogging or improper operation of the machine.

A further object of the invention is to provide a vending machine in which a dispensing mechanism is provided including a plurality of kick-out arms, operated through a series of pawl or cam structures by the manual rotation of a suitable stub shaft and to provide a stop mechanism which is coin operated, for preventing operation of the dispensing mechanism except when a proper coin is inserted therein.

A still further object of the invention is to provide means for returning the kick-out arms to their normal positions after the dispensing of an object, to provide means for preventing improper operation of the machine by reversed rotation of the manually operated stub-shaft.

Other objects of the invention will appear in the following detail description, and in the accompanying drawings wherein:

Figure 1 is a perspective view of the improved vending machine.

Figure 2 is a front elevation of the vending machine with the front side removed.

Figure 3 is a perspective view of the coin controlled object dispensing or vending mechanism.

Figure 4 is a vertical cross section through the object dispensing mechanism taken on the line 4—4 of Figure 2.

Figure 5 is a vertical cross section through the vending machine taken on the line 5—5 of Figure 2.

Figure 6 is a detail horizontal section through the vending machine.

Fig. 7 is a detail view of the dispensing arms.

Referring more particularly to the drawings, the improved vending machine com-

prises a housing 1 which may be constructed in any approved manner.

In the present invention, the combs or other objects to be dispensed or vended are placed in a suitable guide 2, and they are passed downwardly upon the section 3 of the top 4 of the supporting structure 5 of the coin controlled dispensing mechanism by a suitable weight 6, in the same manner in which they are forced upon the top of the dispensing mechanism of the companion application, above referred to. The section 7 of the top 4 is spaced above the section 3 to provide a space 8 between the adjacent edges of the sections 3 and 7, to permit the passage of combs or other articles therethrough and the combs or other articles dispensed are guided by the apron 9 to the dispensing opening 10 in the housing 1.

The combs are abutted through the space 9 by the kick-out or dispensing arms 11, which are rockably mounted upon a suitable shaft 12. The lower ends of the arms 11 are connected by a bar 13 to insure synchronous movement of the two arms. The upper ends of the arms have transversely bent horizontal portions 14 which extend along the undersurface of the section 3, and they have upstanding comb engaging heads 15 mounted thereon which are notched, as shown at 16, to properly engage the combs or other objects to be dispensed one at a time, and force them through the space 9. A stub shaft 17 is rotatably carried by the end 18 of the supporting structure of the coin controlled mechanism and it projects outwardly through the housing 1 and has a thumb button or head 19 thereon to permit its manual rotation. A cam 20 is rigidly mounted on the shaft 17 and engages against the outer surface of the end 18. The cam 20 has a coin receiving portion 21 cut therefrom into which a coin is placed when desired to dispense one of the combs. When the coin is forced into the space 21 through the coin receiving slot 22 in the housing, it will displace the stop 23, which normally engages one edge of the recess 21 and prevents rotation of the stub shaft. The displacement of the stop 23, which is held or urged into stopped position by means of a flat spring 23', will permit the stub shaft 17 to be rotated, and during the initial rotary movement thereof the acute edge of the cam 20 will engage the laterally extended arcuate cam 24 which is formed on the cam arm 25.

110

The cam arm 25 is formed integrally with the arm 11 at the right-hand end of the coin controlled dispensing mechanism, and upon the engagement of the arcuate edge of the cam 21 with the lateral arcuate cam 24, the arms 11 are moved rearwardly to engage the lowermost comb which is resting upon the section 3. The continued rotation of the stub shaft brings the cam 26 which engages against the inner surface of the end 18 into engagement with the cam projection 24 on the cam arm 25 and rocks the arms 11, moving them towards the space 9 for forcing the comb engaged by the shoulders 16 through the space 9 and outwardly through the dispensing opening in the housing 1.

The cam 21 has a straight radial shoulder 28 thereon which is overhung by a hook 29, so that when the stub shaft 17 is rotated in a reversed direction, the shoulder will engage the rear end of the lateral cam 24, while the hook 29 will engage over the upper side of the cam projection 24 and lock the stub shaft 17 and arms 11 against movement, thereby preventing clogging or improper operation of the mechanism.

The flat spring 23' is carried by a plate 33 which is attached to the outer surface of the end 18, and a spacing tongue 34 is struck from the end 18 to co-operate with the plate 33 in properly spacing the coin controlled dispensing mechanism within the housing.

The coins are discharged from the coin receiving recess into cam 23 by the rotation of the cam and the same fall into the bottom of the housing in which they are removed when desired, by removing the front side of the casing 1.

While in the foregoing description, the improved vending machine has been described, as particularly designed for vending combs, it is understood that it may be utilized for vending any analogous articles without departing from the spirit of this invention.

It is, of course, to be understood, that the invention may be constructed in various other manners and the parts associated in different relations, and therefore, I do not

desire to be limited in any manner, except as set forth in the claims hereunto appended.

What I claim is:—

1. In a vending machine, article ejecting arms, a manually rotatable stub shaft, a plurality of cams connecting said stub shaft and arms whereby the arms will be moved into article receiving position upon initial movement of each operation of the stub shaft, a second series of cams for moving said arms into article ejecting position upon continued rotation of said stub shaft, a stop normally preventing rotation of said stub shaft, and means on the first named cams for co-operation with the second named cams to prevent reversed rotation of said stub shaft. 55 60 65

2. In a vending machine, a dispensing mechanism including an inverted U-structure, the top surface of which is cut out to provide an article ejecting space, a cover plate spaced upwardly from and over said ejecting space, a spacing plate between said plate and said top surface adjacent said ejecting space, article ejecting arms having upstanding shoulders formed thereon for engagement against the edge of an article to be ejected, and means for moving said arms simultaneously towards said ejecting space. 70 75

3. In a vending machine, a dispensing mechanism including an inverted U-structure, the top surface of which is cut out to provide an article ejecting space, a cover plate spaced upwardly from and over said ejecting space, a spacing plate between said plate and said top surface adjacent said ejecting space, article ejecting arms having upstanding shoulders formed thereon for engagement against the edge of an article to be ejected, a pair of spaced slots in said top surface at right angles to said ejecting space, said article ejecting arms adapted for movement in said spaced slots, a laterally extending cam arm formed on one of said arms, a laterally bent cam on the free end of said cam arm for operating the ejecting arms simultaneously to eject an article through said ejecting space. 80 85 90 95

In testimony whereof I affix my signature.
HUBERT NOTEBOOM.
